UNITED STATES PATENT OFFICE.

JOHN FRASER, OF BOSTON, MASSACHUSETTS, ASSIGNOR TO HIMSELF AND WILLIAM A. TAR-BETT, COPARTNERS UNDER THE FIRM-NAME OF TARbett AND FRASER.

TYMPAN-SHEET.

No. 896,527.

Specification of Letters Patent. Patented Aug. 18, 1908.

Application filed May 13, 1907. Serial No. 373,338.

To all whom it may concern:

Be it known that I, JOHN FRASER, citizen of the United States, residing at Boston, in the county of Suffolk and State of Massachusetts, have invented certain new and useful 5 Improvements in Tympan-Sheets, of which the following is a specification.

My invention relates to tympan sheets for impression cylinders and the like, and more 10 particularly has for its object to provide a construction whereby the said tympan sheet may be applied to the operative surface of the impression cylinder in a manner permitting the said sheet to be maintained tightly 15 stretched over said surface.

More particularly my invention is made use of in making repairs to impression cylinders, or other cylindrical machine elements, whose operative surfaces have become worn 20 or injured in use. In many cases such injured surfaces may be trued up merely by lathe turning, but in some cases the diminution in the diameter of the impression cylinder caused by the removal of material incident to 25 such a process may render the same unavailable for future use. In such a case it is necessary to first build up the surface of the said cylinder before truing up, and an obvious method of doing this is by attaching to the 30 said operative surface a metal tympan sheet, conforming to the curvature of said surface and having the necessary thickness. Hitherto, so far as I am informed, a tympan sheet so applied to an impression cylinder surface 35 has been attached thereto by screws, rivets, or the like, and although said sheet may be initially securely attached thereby, it will in time loosen up by use.

To remedy this my invention has for its 40 purpose to provide a construction whereby a tympan sheet may be initially tightly stretched over the surface of the impression cylinder to which it is applied, and embodying means whereby said sheet may be again tightened upon said surface in case it becomes loosened by use.

Referring to the accompanying drawings which form a part of this specification, and in which similar reference numerals indicate 50 corresponding parts in all the figures, Figure 1 shows a perspective view of one end of an impression cylinder having a tympan sheet applied thereto in a manner embodying my invention the end of said cylinder nearer the 55 observer being cut away in order to more

clearly show the details of construction of the same. Fig. 2 is a view partly in section, of the cylinder shown in Fig. 1, and illustrating more clearly the details of my invention. Fig. 3 is a view partly in section of a portion 60 of an impression cylinder differing in some respects from that shown in Fig. 1, and showing details of a modified form of construction embodying my invention.

In Fig. 1 is shown one end of an impression 65 cylinder, mounted on a shaft 1, by means of which the said cylinder may be positioned in the printing press. The necessary rigidity is given to the cylindrical operative surface 2 of said cylinder by means of the spoked hubs 70 3 through which shaft 1 passes. The end of said cylinder is preferably solid as shown at 4 in said Fig. 1.

As shown in Figs. 1 and 2 the operative 75 surface 2 of the impression cylinder comprises slightly more than the lower half of the circumference of said cylinder, there being a break on either side of the operative surface forming longitudinal slits 5 opening into the interior of the said cylinder as appears in Figs. 1 and 2. In some cases however said longitudinal slits or openings 5 may be in part or wholly closed, as in Fig. 3, by means of a web 6 lying inside the circumference of the cylinder and extending for a 80 greater or less part of the length of the same.

The tympan sheet 7 is attached to the operative surface of the impression cylinder 11 in the following manner. Said operative 90 surface, if necessary, is first trued up by machining, enough material being removed therefrom to make room for that to be supplied by the tympan sheet. Said sheet, preferably of brass, and of the required dimensions is curved to conform to the curvature of the operative surface, prepared as above, and is fastened at one end to one edge, preferably the gripper edge of the same by means of screws 8, or in any other appropriate manner. 100

The circumferential length of the tympan sheet with relation to that of the operative surface is such that the free end of said sheet overlaps the other, or tail, edge of the operative surface, and the terminal portion of said 105 free end is preferably bent radially inward for a short distance forming a lip 9, as shown.

To the free end of the sheet, and preferably engaging the lip 9, is attached a guide iron 110 preferably consisting of a piece of angle iron

10 having a length equivalent to the breadth of said sheet. Said guide iron 10 comprises the sheet attaching leg 10^b, having the free end of the sheet engaging one surface, while the 5 other, or unengaged surface lies adjacent to the radial portion 17 of the tail edge, and the guiding leg 10^a, which presents a guide surface extending from the sheet attaching leg in the direction of the fixed end of said tympan sheet; that is, in a downward direction 10 as shown in Fig. 2.

Engaging either or both the lip 9 or the sheet attaching leg of the guide iron are the 15 straining means, preferably comprising the set screws 13 bearing against the radial portion 17 of the tail edge of the operative surface, or against some other convenient part of the impression cylinder. Lying closely adjacent to the guiding surface of the guide iron are the guiding means adapted to coöperate with the said guide surface in preventing the rotation of the tightening devices. Said means preferably consist of the pins 12 set into the spokes of the impression cylinder 20 as shown, in Fig. 2, and alined in substantial parallelism with said guiding surface.

When the set screws 13 are first screwed up it will be seen that the force exerted thereby, being out of alinement with the resistance offered by the tympan sheet, will produce a 30 rotation of the lip 9, with the devices attached thereto, in a right handed direction, as shown in Fig. 2, about the corner of said bent over lip 9 as an approximate center. 35 As a result of such rotation the guiding leg 10^a of the guide iron 10 will be brought immediately into contact with pins 12, and the resistance resulting from such contact will prevent any further rotation of said tightening 40 devices about the said corner of the lip 9. As the screwing up of the set screws 13 continues pins 12 will operate to prevent the further rotation of the tightening devices, and thus insures that the force exerted by screwing up 45 the set screws will be applied to the free end of the tympan sheet for the purpose of drawing the same tightly over the operative surface of the impression cylinder.

An analysis of the causes leading to this 50 result shows that as the tightening of the set screws 13 proceeds, the tightening devices will eventually assume a statical condition in which there is a moment, due the tension of the sheet, and tending to rotate the tightening devices about the point of the set screws 13 as a center, which is counterbalanced by 55 the moment of the force with which the guiding leg of the guide iron and pins 12 contact, taken about the same point. From the 60 above analysis it will appear that in order to reduce the intensity of the force with which the guiding leg and the pins 12 contact it is desirable that the point of such contact be as remote as possible from the points of said set 65 screws, and as a matter of fact such point of

contact is usually found to be at the free end of said guiding leg. It is however apparent that a moment adapted to counterbalance the moment set up by the tension in the tympan sheet will theoretically be secured whenever said pins 12 are in contact with the lower surface of the guiding leg, at a point lying to the right of a plane perpendicular to said guiding leg and passing through the point of set screw 13, or, should the pins 12 be arranged to contact with the upper surface of said guiding leg, at a point lying to the left of said plane. That is, the possible range of the point of contact between said guiding leg and the pins 12 may be said to lie between a plane passing through the unengaged surface of the sheet attaching leg of the guide iron, that is, that surface lying adjacent the tail edge 17, and the end of the guiding leg of the said guide iron. 70 75 80 85

I am aware that tightening means have been hitherto employed in analogous situations which somewhat resemble in general appearance and operation the construction of the applicant. In such cases however, the 90 guiding leg of the guide iron extends from the sheet attaching leg of the same in a direction away from the fixed end of the tympan sheet, and not towards the same as in the construction of the applicant. Furthermore it is necessary in such cases that the means for preventing the rotation of the tightening devices extend in the same direction as, and beyond the guiding leg of the guide iron for a distance dependent upon the amount of 100 tightening movement required, and also that the said means be adapted to contact with said guide iron on its outer surface. Such prior constructions therefore require for their installation a space having an angular extent 105 proportioned to the sum of the lengths of the guiding leg and of the means adapted to contact with the same. In my construction, however, the angular extent of the space required for the installation of the tightening 110 devices is substantially dependent of the length of the guide surface alone. Thus for an equal adjustment capacity my construction requires a space of much less angular extent than those heretofore employed. 115 At the same time in my construction the guiding leg of the guide iron and the means engaging the said surface, unlike the prior constructions, are substantially concealed, lying as they do radially inward with respect to the free end of the tympan sheet. Being therefore out of sight in my construction these parts are less obtrusive in the matter of appearance, and afford less opportunity for the lodgment of dirt or refuse, as well as presenting less of an obstacle to the manipulation of a brush or swab when it is desired to clean up that portion of the impression cylinder. 120 125 130

If the tympan sheet stretches or loosens in

use it may be readily retightened by screwing up still further the set screws, and the process may be repeated until the sheet has elongated to such an extent that the guiding 5 leg of the guide iron no longer contacts with the pins 12. In such case the sheet may be shortened, and the angle iron reattached as before in a new position wherein its guiding leg is again in contact with the pins 12, and 10 operates as above described.

In some cases, especially where the presser roll is of the type shown in Fig. 3, it is preferable to substitute in place of one continuous 15 length of angle iron, a number of short lengths of the same individually applied to the free end of the sheet in the manner above described in connection with the cases where the single length is used. In such cases preferably each angle iron is provided with 20 straining means, preferably arranged and operating in the manner heretofore described. Furthermore in such cases it is preferable to cut in the web 6 holes or slits into which the guiding legs of the series of 25 angle irons may be introduced, and which will coöperate therewith in preventing the rotation of the tightening devices, when they are put into operation, in a manner analogous to that described above in connection with 30 Figs. 1 and 2. In said Fig. 3 is also shown a modification of the manner in which the guide iron and straining means may be applied to the end of the tympan sheet. Instead of the bent over lip 9 an angle iron 16 may be 35 attached to the free end of said sheet by screws 15, and to the free leg of this angle iron may be fastened, by rivets 14, one leg of a guide iron 10. The straining means as before are preferably set screws 13 engaging 40 either or both the contacting legs of angle and guide iron, the whole operating as described above more particularly in connection with Figs. 1 and 2.

Having described my invention, what I 45 claim is:

1. In printing machines, in combination with an impression cylinder, a tympan sheet fitting over the operative surface of said impression cylinder and fixed at one end with 50 respect thereto, tightening devices compris-

ing, a guide iron secured to said sheet at its free end, and having a guide surface lying substantially parallel to the said free end of the tympan sheet, and extending in the direction of the fixed end of the same, and 55 straining means engaging said guide iron, bearing against said impression cylinder, and adapted to impart a tightening movement to the said guide iron, and means contacting with said guide surface at that portion thereof lying between a radial plane passing through the point of contact of the straining means with the impression cylinder and the end of said guide surface lying nearer the fixed end of the tympan sheet, and adapted 60 to coöperate with said guide surface in preventing the rotation of the tightening devices. 65

2. In printing machines, in combination with an impression cylinder, a tympan sheet fitting over the operative surface of said impression cylinder and fixed at one end with respect thereto, tightening devices comprising, a guide iron having a sheet attaching leg, one surface of said leg being in engagement with the terminal portion of the free 75 end of the tympan sheet, and the other, or unengaged surface of said leg lying opposite and adjacent to the tail edge of the impression cylinder, and a guiding leg lying substantially parallel to the free end of the tympan sheet, and extending in the direction of the fixed end of the same, straining means engaging said guide iron bearing against said impression cylinder, and adapted to impart a tightening movement to the said guide 80 iron, and means engaging said guiding leg at that portion thereof included between a plane passing through the unengaged surface of the sheet attaching leg, and the end of said guide surface lying towards the fixed 85 end of the tympan sheet, and adapted to coöperate with said guide surface in preventing the rotation of the tightening devices. 90

In testimony whereof I affix my signature in presence of two witnesses.

JOHN FRASER.
